FILM-DEVELOPING TANK

Roy G. Miller, Jr., Sea Cliff, N. Y.

Application June 24, 1949, Serial No. 101,180

1 Claim. (Cl. 95—90.5)

1

It is the principal object of my invention to provide a tank for developing photographic film which is particularly adapted for use by amateur photographers.

I have found that developing tanks heretofore provided for use by amateurs, i. e. adapted for the development of a single film and to be handled in daylight, after the film has been introduced into the tank in the darkroom, require the exercise of a considerable amount of skill in the introduction of the film into the tank. Even a practiced and skillful workman frequently encounters difficulties which result in damage to the film such as fingerprints and scratches.

A more particular object of my invention therefore is to provide a developing tank which requires a minimum of handling of the film and a minimum of skill and practice for the introduction of the film into the tank.

Specifically, an object of my invention is to provide a tank which does not require any threading or winding of the film over or through a supporting structure or any folding or doubling of the film.

A further object of my invention is to provide a flexible tank which can be collapsed and rolled or folded into a small space for storage or transportation and which is strong and durable and unlikely to be destroyed or damaged by accident or rough treatment.

A further object of my invention is to provide a tank which is easy to clean.

A further object is to provide a tank which facilitates the handling of the developing and fixing solutions.

Other incidental objects and/or advantages of my invention will appear from a consideration of the following detailed description of an embodiment of my invention, illustrated in the accompanying drawings, and its mode of operation.

In the accompanying drawings:

Fig. 1 is a vertical section of the tank with its light-tight cover and supporting bracket;

Fig. 2 is an enlarged section of the upper edge 45 of the tank;

Figs. 3 and 4 are a bottom plan view and a vertical cross-section respectively of the light-tight cover;

Figs. 5 and 6 are a top plan view and edge 50 elevation respectively of the tank supporting bracket;

Fig. 7 is a fragmentary section of a modified construction of the tank edge and cover; and

Fig. 8 is a side elevation of the collapsed and partly rolled up tank.

Referring to the drawings, 1 is the tank formed of a flexible liquid- and light-tight sheet material such as polyethylene or other suitable synthetic resin suitably colored or pigmented to render it opaque. The wall of the tank must

2

be sufficiently strong and inelastic to support the weight of the solution. Relatively thick natural or synthetic rubber might be used but I prefer to use a relatively non-elastic but flexible synthetic resin such as the polyethylene or vinyl resins or if an elastic material such as rubber is used I prefer to reinforce it with fabric. It will be apparent also that waterproof coated fabric may be used and in fact any sheet material which is lightproof, liquid-tight, sufficiently strong to hold the film treating solutions without excessive stretching, sufficiently flexible to be rolled or folded and resistant to the chemical action of the film treating solutions.

15 The tank may be constructed in various ways so as to be closed at its lower end and open at its upper end and provided with a more or less rigid ring or bead surrounding its upper end for supporting it. For instance, the lower end of 20 the tank may be molded to hemispherical shape as shown in Fig. 1 or the walls of a thermoplastic tube may be simply heat-sealed or welded together to close the lower end. The edge of 25 the upper end of the tube may be turned around the rigid ring 2 and welded to form the bead 3 as shown in Figs. 1 and 2 or the edge of the tube may be laid over the channel-shaped ring 17 (see Fig. 7) and secured thereto by means of the ring 16 pressed into the channel. The latter construction has the advantage that the tube wall is not worn or abraded by being rubbed by the cover 15.

The mouth of the tank and the opening 5 in the bracket 4 may be of any suitable shape, e. g. circular, rectangular, oval, etc., but since the flexible wall of the tank tends to assume a circular cross-sectional shape when the tank is filled with liquid I have made the mouth of the tank circular as illustrated. An advantage of the circular shape is that it permits the cover 8 or 15 to be rotated to agitate the film suspended therefrom in the solution in the tank while keeping the cover in position to exclude light and, as stated above, the mouth construction illustrated in Fig. 7 has the advantage that the tank wall at the mouth is not worn or abraded by the rotation of the cover 15.

The tank may be of any desired size but for amateur photography I have found a tank about 40 inches long and about 2.5 inches in diameter to be satisfactory. I have further found a normally flat tube formed of polyethylene resin .006 inch thick to be satisfactory. The rings 2, 16 and 17 may be made of polyethylene or other synthetic resin, wood, metal or other suitably rigid and strong material.

The bracket may be made of any suitable material, preferably a non-corrodible material such as stainless steel or synthetic resin, and has a horizontal portion 4 with the opening 5 of the proper size and shape, e. g. circular and 2.5 inch

diameter, to receive and support the tank with the bead 3 or the ring 17 resting on the portion 4. The vertical portion 6 of the bracket is provided with openings 7 for securing the bracket to a wall or other support and preferably is secured to the darkroom wall at a height that will permit the lower end of the tank to rest on the floor.

The cover 8 (Figs. 1, 3 and 4) may be formed of synthetic resin, glass or other suitable material and has the two depending ridges 9 and 10 with the intermediate groove 11 adapted to fit over the bead 3 and exclude light from the tank. The cover is provided with the ring or loop 12 which may be formed of stainless steel wire or other suitable non-corrodible material embedded in or otherwise suitably secured to the cover for supporting the film in the tank.

The cover 15 of Fig. 7 is similar to the cover 8 of Figs. 1, 3 and 4 excepting that the groove 11a between the ridges 9 and 10 is so shaped that the cover rests on the outer edge of the ring 17 and does not rest upon or touch the wall of the tank 1.

When the tank is not in use it may be removed from the bracket 4, 6 and folded or rolled up as shown in Fig. 8 to occupy a relatively small space. In use the tank is dropped through the opening 5 in the horizontal portion 4 of the bracket with the bead 3 or ring 17 resting on the part 4 and filled with the desired treating solution, e. g. developer, fixer or short stop. In this connection I wish to note that in the use of the tank it is preferable to have two tanks, one for developer and one for fixer, with a simple tray for the short stop as will be explained below. A film clip 13 is applied to one end of the film 14 to facilitate handling and to weight it so that it will hang straight in the tank. A second film clip 13 is then applied to the other end of the film and secured to the loop 12 on the cover. The film is then dropped into the tank until the cover rests on the bead 3 or the ring 17. After a suitable time in the developer the film is lifted with the cover, passed through the short stop in the tray referred to and then dropped into another tank containing the fixer.

It is possible with the described arrangement of two tanks and a tray for the developer, fixer and short stop, respectively, to carry out the development of film without having to fill the tank first with one solution and then with another although it is of course possible to use a single tank for all three of the customary developing operations by exchanging solutions. It is possible but not practical to use three tanks, one being for the short stop but since the short stop solution is good for only one time whereas the developer and fixer may be saved and used repeatedly over a long period of time with occasional additions of replenisher it is preferable to use the two tanks for the developer and fixer and a tray, say 8 by 10 inches, for the short stop. It is noted that the film need not be removed from the cover in transferring it from one tank to another but may be transferred with the cover and further that the film-treating liquid in the tank may be agitated by turning the cover with the attached film or by simply squeezing the flexible tank wall.

It is noted that by the use of two tanks and a tray for the solutions as suggested above it is not necessary to fill and empty the tanks through light-tight openings as has been necessary with some of the tank structures heretofore proposed.

Also, the need for drying of the film-supporting structure before the film is introduced is avoided. The filling of the tanks from bottles of solution and the return of the solution to the bottles for storage also is avoided because the solutions may be stored in the tanks between successive developing operations. The tanks of my invention are practically as good as bottles for the storage of the solutions because the area of the solution exposed to the air and the amount of air in the tank are relatively small. For the average darkroom worker the tanks will need to be emptied and refilled with fresh solution only a few times each year and when this is done the tanks may be turned inside out to facilitate cleaning.

The use of two tanks for the developer and fixer which is made convenient by the simple and inexpensive tanks of my invention has the further advantage that it avoids any contamination of either solution by the other and in general greatly simplifies amateur darkroom work and tends to improve the results.

The tanks of the invention are not limited to the size noted above which is suitable for the treatment of a single film but may be made of any desired size for the treatment of any size of film or for treating a plurality of films simultaneously. In fact, two films readily may be treated simultaneously in the tank described by hanging them back to back on the support 12.

I claim:

A photographic film-developing apparatus consisting of a tubular tank the depth of which is at least equal to the length of film to be developed therein and a cover for said tank, said tank consisting of flexible side-walls adapted to be distended to form a tube and to be collapsed and rolled into a compact bundle, said side walls being united at one end to close one end of the tube, the side walls at the other end of the tube being joined to a rigid ring of larger external diameter than said tube whereby said tube is provided with an open mouth at said other end, said ring being adapted to rest on a bracket and thereby to support said tube and its contents, and said cover having an annular groove in one face thereof adapted to fit over said ring and thereby to close said mouth, the inner wall of said groove extending downwardly a substantial distance below said ring and being adapted to engage said bracket through said flexible side walls and thereby to prevent lateral movement of said cover and said ring with respect to said bracket.

ROY G. MILLER, JR.
